UNITED STATES PATENT OFFICE.

JOHN W. B. COLLINS, OF BALTIMORE, MARYLAND, ASSIGNOR TO LAWRENCE E. DAVIS,
OF BALTIMORE, MARYLAND.

CAROUSEL.

1,275,393.

Specification of Letters Patent. Patented Aug. 13, 1918.

Application filed August 31, 1917. Serial No. 189,222.

To all whom it may concern:

Be it known that I, JOHN W. B. COLLINS, a citizen of the United States, residing at Baltimore, State of Maryland, have invented 5 a new and useful Carousel, of which the following is a specification.

This invention relates to carousels.

The principal object of the invention is to provide a device of this character which 10 is strong, durable and simple in construction, which can be easily assembled and disassembled, and wherein the driving mechanism is placed in the most effective position to accomplish the required work.

15 In carrying out this object, the rotating means is mounted upon a yieldable auxiliary frame attached to the passenger frame and running upon a track below the same, the power being supplied by a motor mounted 20 upon the yieldable frame and connected to a suitable source of electrical energy.

In the accompanying drawings I have illustrated one embodiment of my invention, in which:

25 Figure 1 is a plan view.

Fig. 2 is an elevation.

Fig. 3 is a detail elevation of a central mast or post with a hanger attached thereto, with parts in section and with a greater 30 portion of the framework of the carousel omitted.

Fig. 4 is a cross sectional view on the line 4—4 of Fig. 3, looking in the direction of the arrow.

35 Fig. 5 is a detail sectional view of the motor and driving wheel supporting frame.

In the embodiment of the invention here illustrated, the carousel comprises a central mast or post 1 having a base 2 to which are 40 attached the radially extending feet 3. The outer ends of the feet 3 are connected by a circular track or platform 4, as clearly shown in Fig. 1. Projecting from the upper end of the mast 1 is a pointed bearing pin 45 5, constituting a fixed bearing for a rotatable cap 6 provided with a lower central bearing 7 having a pointed socket 8 therein fitting upon the point or pin 5. Hangers or supporting rods 9 are connected at their 50 upper ends to the bearing cap 6 and extend downwardly on slightly diverging lines toward the lower end of the mast or post 1, and at their lower ends they are connected to a suspended bearing ring 10 which encircles the lower end of the mast or post 1.

Fixed at their inner ends to the bearing ring 10 are a plurality of outwardly projecting radially extending horizontal bars or supporting arms 11. To the outer ends of these bars are attached the passenger carrying devices, cars or seats 12.

In order to rotate the passenger carrying frame above described, a pair of adjacent cars 12 are connected by a brace 13. A bifurcated auxiliary frame 14 comprising the arms 15 providing a space between them is attached below the brace 13 by means of downwardly extending resilient arms or braces 17, connected at their upper ends 18 and 19 to the bottom and outside of the brace 13 and at their lower ends to the end of the auxiliary frame 14 remote from the free ends of the arms 15, thereby resiliently supporting the frame 14 in a horizontal position between the brace 13 and the track 70 4. A pulley or driving wheel 20 having a grooved rim is journaled by means of the shaft 21 in the free ends of the arms 15. Fixed to the frame 14 is a motor 22 provided with a driving shaft 23 journaled 80 within suitable bearings 24 upon the frame 14. Fixed to the driving shaft 23 between the arms 15 is a pulley 25 which is connected by means of a belt 26 to the wheel 20. The wheel 20 when rotated is adapted 85 to frictionally engage and bear upon the circular platform or track 4 whereby the carousel is rotated or operated.

In order to supply power to the motor 22, the mast 1 is provided adjacent to its lower 90 end below the bearing ring 10 with fixed contact rings 27, insulated from each other. Conductors 28 lead to both of these rings, while the bottom of the bearing ring 10 is provided with brushes 29, one of which is 95 in engagement with each ring. To the brushes are connected conductors 30 which are connected at their free ends to the motor, whereby power will be supplied to the latter from a fixed source outside of the carousel. 100

Mounted upon the brace 13 above the wheel 20 is a seat 31 having the handle bars 32 in front and adapted to receive a passenger astraddle of the same, as in a bicycle. The driving wheel 20 may be provided with pedals 33 whereby it may be actuated manually, if so desired.

It should be noticed that the contact or driving connection between the track or the platform 4 and the driving wheel 20 is at a 110

point near the outer portions of the carousel and remote from the central mast or post 1. Furthermore, the power is supplied to the driving wheel 20 by means of a motor movable with the passenger frame and which is electrically connected to a suitable source of energy through the central mast. Both the motor and driving wheel 20 are mounted upon a frame yieldably connected to the passenger carrying frame and mounted therebelow, so that the driving wheel is yieldably held against the platform or track 4 and will not be dependent upon the weight of a passenger to cause it to engage and bear against the track.

While I have shown and described one embodiment of my invention, it is to be understood that I do not desire to be limited to the details of construction herein shown and described, for obvious modifications will be apparent to anyone skilled in the art.

What is claimed is:—

1. In a carousel, a central mast, a hanger supported by said mast and having a passenger carrying frame, an auxiliary frame yieldably connected to the outer portions of said carousel beneath said passenger carrying frame, a driving wheel journaled in said auxiliary frame and adapted to run on a track, a motor mounted upon said auxiliary frame, and means for rotating said driving wheel by direct connection with said motor.

2. In a carousel, a central mast, a hanger rotatably mounted upon said mast and provided with a passenger carrying frame, an auxiliary frame yieldably mounted beneath said passenger carrying frame and connected thereto, a driving wheel journaled in said auxiliary frame, a track upon which said

driving wheel runs, a motor fixed to said auxiliary frame and having a shaft journaled therein, and a driving connection between said shaft and driving wheel.

3. In a carousel, a central mast, a passenger carrying frame rotatably mounted upon said mast, an auxiliary frame, resilient arms connecting one end of said auxiliary frame to said passenger carrying frame, a driving wheel journaled on said auxiliary frame, a motor fixed to said auxiliary frame and having a shaft journaled thereon, a pulley fixed to said shaft, a belt connecting said pulley with said driving wheel, and a track beneath said carousel with which said driving wheel engages.

4. In a carousel, a central mast, a hanger rotatably mounted upon said mast, outwardly extending arms attached to the lower end of said hanger, a passenger carrying frame at the outer end of said arms, an auxiliary frame connected to said carousel below said passenger carrying frame, a driving wheel journaled upon said auxiliary frame, a motor also mounted upon said auxiliary frame and having a driving connection with said wheel, a track mounted below said carousel with which said wheel engages, and electrical conductors connecting said motor through the mast with a source of energy outside of the carousel.

In testimony that I claim the foregoing as my own, I have hereto affixed my signature in the presence of two witnesses.

JOHN W. B. COLLINS.
